UNITED STATES PATENT OFFICE.

ROBERT D. SWISHER, OF CHICAGO, ILLINOIS.

DESIGN FOR A WHEEL FOR CASTER STAMP-RACKS.

SPECIFICATION forming part of Design No. 32,883, dated June 26, 1900.

Application filed March 17, 1900. Serial No. 9,113. Term of patent 14 years.

To all whom it may concern:

Be it known that I, ROBERT D. SWISHER, a citizen of the United States of America, and a resident of Chicago, in the county of Cook 5 and State of Illinois, have invented a certain new and original Design for a Wheel for Caster Stamp-Racks, of which the following is a specification.

My invention relates to wheels or revoluble 10 tables for caster-racks for supporting rubber stamps.

In the accompanying drawings, Figure 1 is a plan of such a wheel, and Fig. 2 is a central section.

15 In the said drawings, A designates a central hub, through which there is an axial opening. From the hub A arms B extend to a rim C, and radially, or nearly so, from the rim C extend the arms D. Between the arms D are left the curved spaces E and F, which spaces are left open outwardly, but are inclosed on the other three sides by the arms D and the rim C. The arms D are so arranged with respect to each other that the large spaces E

and small spaces F alternate with each other 25 all of the way around the wheel, and the spaces E and F are so arranged that they are separated from each other only by the arms D.

The leading feature of my design for a wheel for caster-racks consists in the rim C, 30 connected to and supported from the hub A, and in the arms D, projecting laterally from the rim C and terminating in broadened ends, said arms being disposed so as to leave alternate large and small spaces E and F uniformly distributed around the rim C and at substantially uniform distance from the hub A.

What I claim is—

The design for a wheel for caster stamp- 40 racks as herein shown and described.

Signed at Chicago, Illinois, this 15th day of March, 1900.

ROBERT D. SWISHER.
